(57) **CLAIM**

The ornamental design for a cigar box as shown and described.

DESCRIPTION

FIG. 1 is a rear perspective view of the cigar box, showing our new design.

FIG. 2 is a front view of the cigar box of FIG. 1.

FIG. 3 is a rear view of the cigar box of FIG. 1.

FIG. 4 is a right side view of the cigar box of FIG. 1.

FIG. 5 is a left side view of the cigar box of FIG. 1.

FIG. 6 is a top view of the cigar box of FIG. 1; and,

FIG. 7 is a bottom view of the cigar box of FIG. 1.

The evenly spaced broken lines in the drawings depict portions of the cigar box that form no part of the claimed design.
